RACK FOR SMALL PARTS

Fred Morgison, 1010 Court St.,
Clay Center, Kans. 67432

Filed Mar. 8, 1971, Ser. No. 122,265

Term of patent 14 years

Int. Cl. D6—06

U.S. Cl. D33—3

Fig. 2.

Fig. 1.

Fig. 3.
Fig. 4.

FIG. 1 is a perspective view of a rack for small parts embodying my new design;

FIG. 2 is a side elevational view thereof, the opposite side being the same as the side shown;

FIG. 3 is a top plan view thereof; and

FIG. 4 is an end elevational view thereof, the opposite end being the same as the end shown.

I claim:

The ornamental design for a rack for small parts, as shown and described.
